ROTARY DRILL

Carl E. Casperson, Tulsa, Okla.

Application August 22, 1934, Serial No. 740,991

2 Claims. (Cl. 255—19)

This invention relates to rotary drills and has as its object the provision of improved means for rotating a drill stem.

In accordance with the present invention, such a means can be made up of new, salvaged or discarded standard motor truck parts, thus making it an easy matter to replace the parts in case of breakdown or wear.

The invention, together with its objects and advantages, will be best understood from a study of the following description taken in connection with the accompanying drawings, wherein:

Figure 1 is a view in side elevation illustrating the invention mounted on a truck.
Figure 2 is an enlarged detail sectional view through the mechanism for rotating the drill stem.

Figure 3 is a bottom plan view of a collar.

Figure 4 is a top plan view showing somewhat diagrammatically the mechanism for taking power from the transmission of the motor truck.

Figure 5 is an enlarged view partly in section and partly in elevation of the mechanism shown in Figure 4.

Figure 6 is a detail view taken substantially on the line 6—6 of Figure 4.

My invention is especially adapted for use with portable well drilling rigs adapted to be mounted on a truck to be easily transported from place to place.

Thus, in the drawings it will be seen that 5 indicates generally a conventional motor truck, while the reference numeral 6 indicates generally a tower which is pivotally supported on the truck 5 as at 7 through the medium of brackets 8. For supporting the tower 6 when the same is in the horizontal or dotted line position shown in Figure 1, which is the position the tower will occupy when the rig is being transported from place to place, there is suitably mounted at the forward end of the body of the truck a suitable rest 9.

The usual drill pipe or, as it is commonly known, Kelly pipe forming part of the drill mechanism is indicated by the reference numeral 10 and at 45 its upper end is provided with the usual swivel 11 and the suspension cables 12 whereby the pipe 10 is connected to the usual hoisting and lowering cable 13. The cable 13 is trained over suitable pulleys 14 mounted in the upper end of the tower 6 and is windable on a suitable winch 15 (see Figure 5) suitably mounted in the box or body of the truck. The water or other cleaning fluid which is used for flushing the drill bit 16 is fed to the Kelly rod 10 through the usual flexible tubing or piping 17 connected in the usual

manner with the pipe 10. A pump for pumping the water so used is also mounted in the body of the truck 5 and is indicated by the reference numeral 18.

The drill stem is indicated generally by the reference numeral 19 and is connected to the lower end of the Kelly rod 10 in the usual manner as indicated generally at 20.

My improved mechanism for rotating the drill comprises a sectional housing 21 which, in the present instance, is made up of sections used in the construction of a differential housing for motor vehicles. On the tubular part 21a of the housing 21 is a collar 22 provided internally with the shoulder 23 between which and the end of the part 21a of the housing is a thrust bearing 24 that is also held in position through the medium of a suitable bushing 25.

A somewhat similar collar 26 is provided on the tubular end 21b of the housing or casing 21 and also is equipped with a shoulder 27, thrust bearing 28 and bushing 29. Extending through the housing or casing 21 is a tube 30 onto the ends of which are screwed as at 31 and 32 the aforementioned collars 22 and 26. Welded or otherwise fixedly secured to the sleeve or tubing section 30 is a ring gear 33 that is, or may be nothing more or less than the driving gear such as, for example, is used in differentials for "Ford" motor trucks.

The gear case 21 is also provided with the usual pinion pilot bearing 34, pinion bearing 35 and pinion bearing cup 36 supporting in the usual manner the driving pinion 37 that is in constant mesh with the ring gear 33.

I also make use of the usual drive shaft coupling 38, bearing nuts 39 and bearing sleeve 40.

The mechanism just described is suitably mounted on the rear end of the truck 5 and is adapted to have passed through the sleeve 30 40 the Kelly rod 10 which, as will be understood, is of the usual cross sectional shape, namely, square.

For operatively connecting the sleeve 30 with the rod 10, there are provided a pair of complementary slips 41 that are accommodated in the bores of the collar 22 and the upper portion of the sleeve 30, the slips 41 having rounded or convex outer surfaces and squared or substantially rectangular inner surfaces or grooves 42 which 50 accommodate the Kelly rod 10. Further, at the upper ends thereof the slips 41 are provided with lateral flanges 43 that are accommodated in a groove 44 extending transversely of and provided in the upper end of the collar 22. Thus it will 55

be seen that rotation of the sleeve 30 will be transmitted to the rod 10 for rotating the drill parts 16 and 19, the part 19, or stem of the drill, being, as before stated, connected as at 20, with 5 the lower end of the Kelly rod 10.

Further, in accordance with the present invention, the coupling 38 serves to operatively connect the pinion 37 with a shaft section 45 that is driven through the medium of chain and sprocket 10 means 46 from a shaft 47, shafts 45 and 47 being suitably mounted on the truck. For placing the shaft 45 into and out of driving engagement with the shaft 47 there is provided as a part of the chain and sprocket mechanism 46 a suitable 15 clutch 48 that is operated by the driller through the medium of a suitable control rod 49.

For driving the shaft 47 there is suitably associated with the transmission 50 of the truck a power take-off device 51 which is suitably connected as at 52 with the shaft 47.

For driving the pump 18 from the shaft 47 there is provided a chain and sprocket mechanism 53 including a suitable clutch 54 operated through the medium of a control or operating 25 rod 55.

For driving the winch 15 from the shaft 47 there is provided suitable power transmitting mechanism including a chain and sprocket mechanism 56 embodying as a part thereof a 30 clutch 57 which is also equipped with a suitable control rod (not shown).

From the above it will be apparent that when the parts are in the position shown in Figure 1, power for operating the drill is taken through 35 the medium of the mechanism just described from the transmission 50 of the truck for driving the pinion 37 which, being in mesh with the ring gear 33, rotates the sleeve 30 resulting in a rotation of the drill rod 10 and the associated 40 drill.

To insure lubrication of all moving parts of the device, the casing 21 will be fluid tight and will retain oil to a suitable level. To this end there is provided within the casing 21 an oil retaining tube 60 which is disposed concentric to the tube 30 and spaced relative thereto. The tube 60 is secured at one end in any suitable man-

5 ner within the casing 21 in substantial alignment with the extension 21b and extends inwardly to within a short distance of the flange 33 as shown in Figure 2. With the tube 60 so arranged in the casing, the casing or housing 21 may be filled with oil up to the top of the tube 60 which will create an oil level sufficiently high to submerge the pinion 37 and the tooth-equipped part of the ring gear in oil, thus supplying sufficient lubrication to all parts of the rotary drill except the 10 caps 22 and 26.

What is claimed is:

1. In a drilling mechanism, a gear case, a sleeve rotatably mounted therein, gearing within the case and operatively connected with the 15 sleeve for driving the latter, a collar on one end of the sleeve having a circular bore, and also provided on one end with grooves at diametrically opposite sides of the bore, and a pair of complementary slips fitting in the bore of the collar and having at one end lateral flanges engaging in the groove of the collar; said collar also having a skirt portion telescoping a fixed portion of said casing and a thrust bearing arranged within the 20 confines of the skirt portion of the collar at one end of the fixed portion of said casing.

2. In a mechanism of the character described, a casing, a tubular member extending through said casing having ends projecting beyond the corresponding ends of the casing, collars threaded on the projecting ends of the tubular member, said collars having skirt portions telescoping adjacent end portions of said casing, thrust bearings confined between said collars and the ends of the casing within the confines of the skirt of the collars, one of said collars having diametrically disposed grooves in an end face thereof, complementary slips extending through said one collar into said tubular member and having at one end lateral flanges engaging in the grooves of said one collar, and an oil tube fixed within said casing concentric to said tubular member, said oil tube being fixed at one end within one end of said casing and terminating at its free end in spaced relation to the relatively opposite 45 end of said casing.

CARL E. CASPERSON.
